UNITED STATES PATENT OFFICE.

MAX BALDAUF, OF PLAUEN, GERMANY, ASSIGNOR TO PERLMANN, SCHAL & STERN, OF NEW YORK, N. Y., A COPARTNERSHIP COMPOSED OF NICHOLAUS PERLMANN, GEORGE SCHAL, AND HERMAN STERN.

DESIGN FOR MACHINE EMBROIDERY.

Application filed July 15, 1922. Serial No. 3,089. Term of patent 3½ years.

To all whom it may concern:

Be it known that I, MAX BALDAUF, a citizen of the Republic of Germany, residing at Plauen, Saxony, Germany, have invented a new, original, and ornamental Design for Machine Embroidery, of which the following is a specification, reference being had to the accompanying drawing, forming part thereof.

The figure is a plan view of a piece of embroidery, constituting my new design.

I claim:

The ornamental design for machine embroidery as shown.

MAX BALDAUF.
